(57) **CLAIM**

We claim the ornamental design for an eyewash device, as shown and described.

DESCRIPTION

FIG. 1 is a perspective view of the claimed design;
FIG. 2 is a top view thereof;
FIG. 3 is a bottom view thereof;
FIG. 4 is a front view thereof, the rear view being identical to FIG. 4; and,
FIG. 5 is a right side view thereof, the left side view being identical to FIG. 5.

The ornamental design which is claimed is shown in solid lines in the drawings. The broken lines in the drawings are for illustrative purposes only and form no part of the claimed design.

1 Claim, 4 Drawing Sheets
